Horace Barnes
ATTORNEY

UNITED STATES PATENT OFFICE.

APOSTOLOS C. ITHOMITIS, OF RAYMOND, WASHINGTON.

AUTOMATIC FIREARM.

Application filed December 5, 1921. Serial No. 519,830.

To all whom it may concern:

Be it known that I, APOSTOLOS C. ITHOMITIS, a citizen of Greece, but who have declared my intention to become a citizen of the United States, and resident of the city of Raymond, in the county of Pacific and State of Washington, have invented certain new and useful Improvements in Automatic Firearms, of which the following is a specification.

This invention relates to improvements in automatic firearms, and particularly to improvements in shot-guns wherein the shells contained in the magazine are delivered into the firing chamber singly and in repetition as the shells are fired and ejected. The recoil of the exploding shell furnishing energy to perform the successive acts of loading, firing and ejecting.

The object of the invention is the provision of simple and effective means to accomplish the said successive functions of firing the initial discharge, utilizing the recoil to eject the shell and reload, and to fire the following shell.

Other objects of the invention will be apparent in the course of the following specification of the invention, wherein the invention consists in the novel construction of an automatic fire-arm of the class described, and the adaptation and combination of parts and devices to carry out the aforesaid results, as will be fully described in the following specification illustrated in the accompanying drawings, and finally set forth in the appended claims.

In said drawings, Figure 1 is a fragmentary view in side elevation of a shot-gun embodying my invention, shown partly in longitudinal section to disclose the interior of the gun, said view showing the working parts in firing positions.

Fig. 2 is a view similar to Fig. 1, illustrating the working parts in positions prior to a new shell entering the firing chamber.

Fig. 3 is a view in side elevation of my improved shot-gun.

Fig. 4 is a fragmentary view in horizontal section showing the extraction of a shell.

Figs. 5, 6, and 7 are views in cross-section on lines 5—5, 6—6, and 7—7, respectively of Fig. 4.

Fig. 8 is a vertical sectional view on line 8—8 of Fig. 2.

Fig. 9 is a horizontal sectional view of the reciprocating bolt.

Fig. 10 is a view in side elevation of the bolt.

Fig. 11 is a front end view of the bolt.

Fig. 12 is a rear end view of the bolt.

Fig. 13 is a detached view of the trigger and connecting parts.

Referring to said views, in which like characters of reference denote like parts in the several views, the reference numeral 1 designates the stock of a shot-gun of my invention and 2 the barrel provided with a bore 3 of ordinary or suitable construction.

Connecting said stock and the barrel is a casing 5 including a chamber 6 for the trigger actuating mechanism and a magazine chamber 7. To the rear of said barrel and in axial alignment therewith is breech-chamber 8 and in parallel therewith is a recoil chamber 10. Said chambers 8 and 10 are

connected by a slot 11 and in the breech-chamber 8 of circular configuration in cross-section is a bolt 12 arranged to reciprocate therein and provided with an arm 13 extending into recoil chamber 10 and formed with a stud 15.

A corresponding stud 16 is formed at the rearward end of said chamber 10. A compression coil-spring 17 is mounted at opposite ends on said studs and serves to absorb the recoil of the explosive shell upon said bolt and to cause the latter to rebound to fire the next successive charge.

18 indicates an arm extending horizontally through a slot 20 in the side wall of the gun-breech through which the bolt may be manipulated by hand. Said bolt is formed with an interior chamber 21 to receive a firing-pin 22. Said pin is of relatively reduced size excepting for a collar 23 which is formed for a sliding fit within said chamber 21. A coil spring 25 is confined between said collar and the rear end of said chamber 21 tending to urge said pin forwardly. Reduced apertures are formed at the front and rear ends of said chamber 21, as at 26 and 27, respectively.

Aperture 26 admits of the front pointed end of the firing pin to protrude therethrough to penetrate the fulminating cap of the shell and aperture 27 forms a rear sliding bearing for the pin. The rear end of said firing pin exteriorly of the bolt is provided with a head 28 having a downwardly directed lug 30.

31 indicates a trigger pivoted at 32 within chamber 6 and protected by guard 33. 35 indicates a spring tending to urge said trigger in its forward inoperative position. Con-

nected to said trigger within chamber 6 is an upturned finger 36 having a limited hinged movement on its connection 37 with said trigger and yieldingly pressed in its 5 rearmost position by a flat spring 38. When the trigger is actuated, said finger is arranged to engage a star-wheel 40 having points 41 of rounded extremities at points offset forwardly of the radius of said wheel 10 so that the wheel will be given a partial rotation at each impulse of the trigger. Pivoted at 42 above the wheel is a rocking lever 43 whose rearward arm is provided with an anti-friction roller 45 normally engaging in 15 the depressions between said star-points 41 of the wheel. The opposite arm of said lever is provided with a right angularly directed dog 46 extending through a slot 47 into the path of said lug 30. The forward end of 20 said lever is yieldingly maintained in its uppermost position by means of a spring 48. 50 indicates a sliding safety catch arranged to be moved into a notch 51 in the trigger whereby the latter cannot be actuated accidentally.

The magazine chamber 7 is communicatively connected to the breech-chamber of the gun by an opening 52 and is closed at its bottom by means of a plate 53 hingedly connected to the casing at 55 and secured by a 30 spring catch 56. Connected to said plate is a flat folded spring 57 supporting a pan 58 upon which the shells are disposed in superimposed order. Spring guide members 59 are secured at 61 to the sides of the magazine, and serve to maintain said shells in aligned position.

62 indicates an extractor pivotally connected at 63 to the bolt arranged to rock 40 slightly on said connection through the action of a coil spring 65. The extractor head 66 is arranged to seize the rim of the shell and withdraw the shell until the latter is opposite the side opening 67 of the breech 45 whereupon the opposite edge of said rim will strike upon a pin 68 which will enable the extractor head to pull the shell sidewise through opening 67 and away from the gun, as shown in Fig. 4. A slot 70 is formed in 50 the bolt to accommodate the passage of the bolt by said pin 68.

Said bolt 12 may be formed in two parts for convenience in manufacture and assembling. The forward part 12' is formed with 55 a rib 71 having a portion 72 extending rearwardly over the main portion of said bolt and is slotted at 73 to accommodate a key 75 rigid with bolt 12 and in longitudinal alignment therewith. Said rib and key are arranged to slide with the bolt in slot 76 of the breech chamber.

The operation of my improved gun may be described as follows: Referring to Fig. 1 where a shell is shown in the firing chamber 65 71, the bolt is "cocked" preparatory to firing

by pulling back the bolt 12 by means of the arm 18 until the lug 30 engages and is retained by the dog 46. As said arm is released, the power of spring 17 asserts itself to move the bolt forwardly of the breech-chamber while the firing pin is retained by the dog 46 to compress the spring 25. As the trigger is pulled by means hereinafter explained, the dog 46 releases the lug 30 and the power of spring 25 asserts itself to 70 impel the firing pin forwardly to pierce the shell-cap and fire the charge. The recoil of said discharge reacts upon the bolt 12 and forces it backward in the breech-chamber and against the compression of spring 17 75 until the force of the recoil is absorbed, whereupon the power of spring 17 will assert itself and cast the bolt forwardly again to fire the succeeding shell. The gun will continue firing as long as the trigger is held, 80 and the dog 46 depressed out of the line of travel of the lugs 30.

Said trigger when pulled in the ordinary manner forces the finger 36 against one of the star-points 41 of the wheel 40 and gives 90 said wheel a partial rotation. In doing so, the wheel elevates the rear arm of lever 43 through the roller 45 travelling over one of said star-points and thereby actuates the dog 46 to release the firing pin. There is 95 sufficient tension in spring 48 to cause said roller 45 to move said star-wheel so that the roller will again occupy one of the depressions in said wheel, unless the trigger is retained.

As one shell is being ejected by having its forward end swing about and out of the gun through the slot 20, the forward end of a new shell is protruded upwardly towards the shell chamber, and as soon as the shell 105 is completely ejected, the spring pressure below forces the same upwardly in position for the bolt 12 to push it into the shell chamber preparatory to firing.

The advantages residing in my improved gun are numerous, and in part consist in the relative simplicity of its construction, and the accessibility of all parts to inspection and repair. It is not liable to get out of order, may be reloaded with ease, and will 110 fire and repeat with safety and reliability.

While I have described my invention briefly, I wish to be understood to include in the scope thereof all changes and modifications that may reasonably suggest themselves 115 within the spirit of the invention, and the terms of the claims.

Having described my invention, what I claim as my invention, is—

1. An automatic shot-gun including a barrel, a breech-chamber in axial alignment therewith, and a recoil chamber parallel with said breech-chamber, a chambered bolt formed with an arm extending outwardly of the breech-chamber and an arm extending in 120

said recoil chamber, a compression-spring in said recoil chamber arranged to exert its force upon said bolt through said last named arm, a firing-pin mounted in the chambered portion of said bolt and provided with a lug at its rear end exteriorly of the bolt, a coil spring tending to urge said pin forwardly, a trigger having an upturned finger yieldingly connected thereto, a star-wheel arranged to be actuated in partial rotation by said trigger-finger, a spring-compressed lever having a dog arranged to engage and releasably retain said firing-pin lug, said lever being provided with a roller normally engaging within one of the depressions between the points of said star-wheel and arranged to be actuated to rock said lever and release said dog from said lug as said wheel is rotated, an extractor on said bolt, a pin in the path of the shell being ejected and upon the side opposite the extractor, to act as a stop and fulcrum to eject the shell, a magazine having an opening in its lower end, a closure for said opening, a flat bent spring retained in said magazine, a plate for lifting the shells supported on said flat spring, and spring guides at the sides of said magazine.

2. An automatic shot-gun including a barrel, a breech-chamber in axial alignment therewith and a recoil chamber parallel with said breech-chamber, a chambered bolt formed with an arm extending outwardly of the breech-chamber and an arm extending in said recoil chamber, a compression-spring in said recoil chamber arranged to exert its force upon said bolt through said last named arm, a firing-pin mounted in the chambered portion of said bolt and provided with a lug at its rear end exteriorly of the bolt, a coil spring tending to urge said pin forwardly, a trigger having an upturned finger yieldingly connected thereto, a star-wheel arranged to be actuated in partial rotation by said trigger-finger, a spring-pressed lever having a dog arranged to engage and releasably retain said firing-pin lug, said lever being provided with a roller normally engaging within one of the depressions between the points of said star-wheel and arranged to be actuated to rock said lever and release said dog from said lug as said wheel is rotated, means to eject the shell, a magazine having an opening in its lower end, a closure for said opening, a flat bent spring retained in said magazine, a plate for lifting the shells supported on said flat spring, and spring guides at the sides of said magazine.

3. An automatic shot-gun including a barrel, a breech-chamber in axial alignment therewith and a recoil chamber parallel with said breech-chamber, a chambered bolt formed with an arm extending outwardly of the breech-chamber and an arm extending in said recoil chamber, a compression-spring in said recoil chamber arranged to exert its force upon said bolt through said last named arm, a firing pin mounted in the chambered portion of said bolt and provided with a lug at its rear end exteriorly of the bolt, a coil spring tending to urge said pin forwardly, a trigger having an upturned finger yieldingly connected thereto, a star-wheel arranged to be actuated in partial rotation by said trigger-finger, a spring-pressed lever having a dog arranged to engage and releasably retain said firing-pin lug, said lever being provided with a roller normally engaging within one of the depressions between the points of said star-wheel and arranged to be actuated to rock said lever and release said dog from said lug as said wheel is rotated, an extractor on said bolt, a pin in the path of the shell being extracted and upon the side opposite the extractor to act as a stop and fulcrum to eject the shell, a magazine for shells, and means to feed shells from said magazine to the firing-chamber.

4. An automatic shot-gun including a barrel, a breech-chamber in axial alignment therewith and a recoil chamber parallel with said breech-chamber, a chambered bolt formed with an arm extending outwardly of the breech-chamber and an arm extending in said recoil chamber, a compression-spring in said recoil chamber arranged to exert its force upon said bolt through said last named arm, a firing-pin mounted in the chambered portion of said bolt and provided with a lug at its rear end exteriorly of the bolt, a coil spring tending to urge said pin forwardly, a trigger having an upturned finger yieldingly connected thereto, a star-wheel arranged to be actuated in partial rotation by said trigger-finger, a spring-pressed lever having a dog arranged to engage and releasably retain said firing-pin lug, said lever being provided with a roller normally engaging within one of the depressions between the points of said star-wheel and arranged to be actuated to rock said lever and release said dog from said lug as said wheel is rotated, an extractor on said bolt, a pin in the path of the shell being extracted and upon the side opposite the extractor to act as a stop and fulcrum to eject the shell, a magazine for shells, and means to feed shells from said magazine to the firing-chamber.

Signed in Raymond, Washington, this 19th day of September, 1921.

A. C. ITHOMITIS.
